UNITED STATES PATENT OFFICE.

FRANK G. WHEELER, OF APPLETON, WISCONSIN, ASSIGNOR TO BLEACH PROCESS COMPANY, OF APPLETON, WISCONSIN, A CORPORATION OF WISCONSIN.

ELECTROLYTIC CELL.

1,236,025.

Specification of Letters Patent. Patented Aug. 7, 1917.

Application filed October 30, 1915. Serial No. 58,803.

To all whom it may concern:

Be it known that I, FRANK G. WHEELER, a citizen of the United States, residing at Appleton, in the county of Outagamie and 5 State of Wisconsin, have invented certain new and useful Improvements in Electrolytic Cells, of which the following is a specification.

This invention relates to electrolytic cells, 10 and particularly to cells of the diaphragm type which are primarily intended for the production of caustic alkali solutions and chlorin by electrolyzing solutions of alkali chlorids. A primary object of the invention 15 is to provide a cell construction in which the cathode is relieved of all strains due directly or indirectly to the weight of the cell-cover or of the anodes; and in which such cell-accessories as the brine-feed, the 20 liquid-level indicator, the chlorin-outlet and the like, or some of them, may be mounted in the interior of the cell instead of at its peripheral portion, as has been the usual practice heretofore. In the embodiment 25 which is preferred for cells of large size, the cell is substantially circular in contour, the chamber for containing the electrolyte assuming the general form of an annulus surrounding a central well in which the 30 necessary connections and accessories, including if desired the electrical connections for the anodes, may be carried.

Certain forms of cell embodying the invention are shown in the accompanying 35 drawings, wherein Figures 1, 2 and 3 are central vertical sectional views of three illustrative embodiments of the invention, like numerals indicating corresponding parts in all of the figures.

40 In Fig. 1, I have shown a cylindrical cell comprising a base plate 1, a cover 2, and a central hollow column 3 which supports the cover. All of these parts are made of a material which is capable of withstanding 45 chlorinated brine, as stoneware, cement compounds, or if desired iron faced with rubber, etc. As illustrated in this figure the central column 3 is separable from the base and cover, and is properly positioned with 50 reference to these by shallow circular or annular grooves 4. The anodes 5, usually of graphite, are carried by the cover 2, and therefore indirectly by the column 3. A cylindrical perforated cathode 6, with its as-

sociated diaphragm 7 completely surrounds 55 the anode or electrolyte compartment, being secured at the bottom to the peripheral portion of the base plate 1, and at the top to an annular flange 8 which surrounds the cover. In the particular form illustrated 60 this flange 8 is separate from the cover and projects slightly above the same, and also depends below the chlorin passages 9. The flange may however be integral with the cover. A casing 10, usually of sheet metal, 65 surrounds the cathode, assuming in this particular case the form of a vessel or container for the parts above described. This casing is provided with a bottom outlet 11 for the caustic solution and with a top aperture 12 70 for the escape of hydrogen.

It will be observed that in this construction the cathode is carried by the base plate of the cell, and is quite free to expand or contract under changes of temperature without incurring strains due to the weight of the cover or of the anodes, which are independently supported by the column 3. The cover of the cell may be luted, as indicated 75 at 13, the luting being sufficiently plastic to 80 permit any necessary relative movement as between the cover 2 and the flange 8.

14 represents a brine-feed pipe leading to the interior of the hollow column 3. This is shown as somewhat constricted about 85 midway of its height, and provided at the constricted portion with a plurality of apertures 15 through which the fresh brine is distributed to the anode compartment. A further advantage of this construction is 90 that the cover, with the anodes carried thereby, may be readily removed, as may also the column 3, thereby exposing all the interior portions of the cell for inspection, cleaning or repair. 95

The construction of Fig. 2 is well adapted for cells of larger size and is in general similar to that above described. In this case the central column 3 is substantially cylindrical, flaring outwardly at its upper portion, and forms a liquid-tight connection with the base 1, this construction allowing the central portion of the cell to take the form of an open well. The brine in this case is fed directly through conduit 14 to the annular anode chamber, and the chlorin is drawn off downwardly through conduit 16. 100 17 represents a level-indicator for the elec- 105

trolyte. The anodes 5 are supported directly from the column 3, the electrical connections thereto being made through conductive pins 18 which may be of graphite or of metal.

5 In this construction therefore the interior of the column 3 is free from liquid, and carries all of the usual cell-accessories, including the anode connections.

Fig. 3 embodies the general construction 10 of Fig. 2, with the exception that the base 1 is sectional, comprising a central portion 1^a and a peripheral annulus 1^b, the two parts interlocking in a liquid-tight manner. The ring 1^b is separable from the inner portion 15 of the base plate, and carries the cathode and diaphragm 6, 7, as well as the cathode casing 10. As will readily be seen, this construction permits the cathode with its associated parts to be removed without dis- 20 mounting the cell other than by disconnecting the cathode lead and the caustic line. While in Fig. 3 I have shown the anodes as carried by the cell-base 1, it will be under- 25 stood that they may be supported either from the cover as in Fig. 1, or from the central column as in Fig. 2. It is a feature common to all of the constructions that the working parts of the cell are very readily accessible.

30 The foregoing are merely illustrative embodiments of my invention which may be variously modified in design. The use made of the free interior space provided by the central column in Figs. 2 and 3 will of course depend in a measure upon the size of the cell; and in large cells all of the accessories, including if desired a fixed - level brine-feed, may be located in this interior space. It will also be understood that the 35 several elements herein referred to as cell accessories are merely illustrative of their kind, and may be modified as desired in form and construction. For example, the gas-connections, brine-inlet and the like may 40 assume the form of channels or conduits cored into the casting.

In all of the constructions illustrated the cover is carried directly by the interior column, and in Fig. 2 the anodes are also carried by this column. These constructions are particularly advantageous in connection with cells of the diaphragm type, inasmuch as the cathode is free to expand and contract unhindered by the weight of the cover 50 and of the anodes; this relieves the cathode of strains which might cause a slipping of the joints and the rupture of the diaphragm at these joints, or which might lead to deformation of the cathode itself. Furthermore, even in the larger sizes of cells, the various parts may be made so light as to be 55 readily handled; thus the base plate which carries the diaphragm may be a ring instead of a disk; the central column is detachable 60 and may be separately handled, the anodes

are separately mounted; and if desired the annular covers may be made in sections for convenience in handling.

The apparatus may be otherwise modified as will be apparent to those skilled in this 70 art. For example, the function of supporting the cover as well as the anodes independently of the cathode can be secured in a construction such as is illustrated in Fig. 1 by the use of one or several solid columns; so 75 that although I prefer to employ hollow columns on account of the additional advantage thereby secured, my invention is not restricted thereto.

If desired, the central column in any of 80 the constructions may be cast or formed integral with the base or with the cover, or with either of these; so that the terms "base" and "cover" as employed herein are not restricted to separate or separable elements, 85 but refer broadly to such cell portions as perform the corresponding functions.

I claim:—

1. An electrolytic cell having a base, a combined cathode and diaphragm, an anode, 90 a cover, and means located in the interior of the cell for supporting said cover independently of said cathode and diaphragm.

2. An electrolytic cell having a base, a combined cathode and diaphragm carried 95 thereby, an anode, a cover, and means located in the interior of the cell for supporting said anode and cover independently of said cathode and diaphragm.

3. An electrolytic cell having a base, a 100 cathode, a cover, and means comprising a hollow column located in the interior of the cell for supporting said cover independently of said cathode.

4. An electrolytic cell having a base, a 105 cathode carried thereby, an anode, a cover, and means comprising a hollow column located in the interior of the cell for supporting said anode and cover independently of said cathode.

5. An electrolytic cell having a base and cover, a combined cathode and diaphragm extending between the base and cover, and means located in the interior of the cell for supporting said cover independently of said 115 cathode.

6. An electrolytic cell having a base and cover, a combined cathode and diaphragm extending between the base and cover, and means comprising an open-ended hollow 120 column located in the interior of the cell for supporting said cover independently of said cathode.

7. An electrolytic cell provided with a base plate having a separable rim of non- 125 conductive or insulated material, and a cathode carried by said rim and removable therewith.

8. An electrolytic cell provided with a base plate having a separable rim of non- 130

conductive or insulated material, and a combined cathode and diaphragm carried by said rim and removable therewith.

9. In an electrolytic cell, the combination 5 of an internal feed cup, located within the anode compartment, an anode supporting means carried on said internal feed cup, anodes carried by said supporting means, said anodes being located external to the 10 feed cup.

10. An electrolytic cell comprising a cylindrical anode compartment, an internal feed cup within said anode compartment, and anodes having a support carried on said 15 internal feed cup.

11. An electrolytic cell comprising an anode compartment and a removable cover for the anode compartment, an internal feed cup for the anode compartment, electrodes 20 depending from the cover, said cover being supported directly upon the internal feed cup.

12. In an electrolytic cell, a container, a cathode-diaphragm within said container 25 forming one wall of an anode vessel, a removable anode cover for the anode vessel, anodes depending from the cover, said cover being supported independently of and at an elevation lower than the upper marginal 30 edge of the cathode-diaphragm thus permitting the anodes to be immersed in the electrolyte throughout their length below the cover.

13. In an electrolytic cell, a cathode-diaphragm forming the wall of an anode ves- 35

sel, a bottom for the anode vessel, a cover for the anode vessel, a vertical member resting upon the bottom of the anode vessel, said vertical member serving as a support for the anode cover, whereby said anode 40 cover is supported independently of the wall of the anode vessel.

14. In an electrolytic cell, a cathode-diaphragm forming the wall of an anode vessel, a bottom for the anode vessel, means 45 for supporting an anode cover, said means being supported wholly on the bottom of the anode vessel.

15. In an electrolytic cell, a cathode-diaphragm forming the wall of an anode ves- 50 sel, a bottom for the anode vessel, an anode supporting means, said anode supporting means being carried wholly on the bottom of the anode vessel and anodes carried by the supporting means, said anodes being 55 located between the supporting means and the cathode diaphragm.

16. In an electrolytic cell, the combination of an electrode compartment, an internal feed cup located within the electrode compartment, an electrode supported on the feed cup and extending into the electrode compartment externally of the feed cup. 60

In testimony whereof I affix my signature in presence of two witnesses.

FRANK G. WHEELER.
